SHEET FEEDING AND TRANSFERRING
MEANS

Richard C. Talbot, Joliet, Ill., assignor to Wright's Automatic Tobacco Packing Machine Company, Durham, N. C., a corporation of North Carolina

Original application August 3, 1940, Serial No. 350,782. Divided and this application March 12, 1941, Serial No. 383,035

18 Claims. (Cl. 271—12)

The present invention relates to improvements in sheet feeding and transferring means, and is applicable generally to the feeding of sheets such as stamps or labels from a magazine and transferring them to a point where they are to be applied to bottles or other containers, or otherwise employed or operated upon.

The invention is more particularly adapted for feeding and transferring revenue stamps or other sheet-like objects to bottles in a machine of the type shown and described in my prior application Ser. No. 350,782 filed August 3, 1940, of which this application is a division.

In the drawings:

Fig. 1 is a front elevation of a bottle stamping machine having applied thereto stamp feeding and transferring means constructed in accordance with the present invention;

Fig. 2 is a top plan view of the machine as shown in Fig. 1;

Fig. 3 is a detail view of the driving means for the machine, this view being a horizontal section taken on the line 3—3 in Fig. 1;

Fig. 4 is an elevation, on an enlarged scale and partly in section, of the stamp feeding and gumming mechanism and a portion of the stamp transferring means which conveys the stamps to the bottles on the turntable;

Fig. 5 is a vertical section taken on the line 5—5 in Fig. 4;

Fig. 6 is a horizontal section taken on the line 6—6 in Fig. 4;

Fig. 7 is a diagrammatic view showing the cams which oscillate the stamp magazine and control the operation of the stamp gripper;

Fig. 8 is a detail vertical section taken through the lower portion of the stamp magazine on the line 8—8 in Fig. 4;

Fig. 9 is a detail vertical section taken on the line 9—9 in Fig. 8;

Figs. 10, 11 and 12 are detail views of the stamp magazine and stamp gripper, showing the successive relative positions of these parts while removing the stamp from the magazine and engaging it with the gripper;

Fig. 13 is a detail vertical section through the stamp magazine, taken on the line 13—13 in Fig. 10;

Figs. 14, 15 and 16 are detail vertical sections through the stamp gripper, on an enlarged scale, showing diagrammatically the manner in which the gripper removes a stamp from the magazine and delivers it to the stamp transferring means;

Fig. 17 is a top plan view of the stamp gripper;

Fig. 18 is a detail section taken on the line 18—18 in Fig. 14;

Fig. 19 is a fragmentary detail section taken on the line 19—19 in Fig. 16;

Fig. 20 is a detail view of the mechanism co-operative with the stamp transferring means for releasing the stamp therefrom when positioned above a bottle on the turntable;

Fig. 21 is a cross section taken on the line 21—21 in Fig. 20;

Fig. 22 is a perspective view of one of the stamp carriers on the stamp transferring means;

Fig. 23 is a detail section taken longitudinally through one end of one of the stamp carriers, indicating by the dotted and full lines the operation of one of the stamp impaling pins; and

Fig. 24 is a perspective view of a form of stamp which the machine is adapted to apply to bottles.

Similar parts are designated by the same reference characters in the different figures.

The bottle stamping machine, to which the present invention is shown applied as an example of one manner of using the invention, comprises a frame 1 which supports a track 15 which extends longitudinally thereof, and a bottle conveyor 16, comprising an endless chain 17 having platforms 18 thereon for supporting the bottles, is arranged to travel longitudinally along this track in a direction from the left toward the right in Fig. 1. This conveyor chain passes around a driving sprocket 19 mounted in suitable bearings at one end of the main frame and which drives this conveyor chain continuously in the direction stated, and the other end of this conveyor chain passes around an idler sprocket (not shown), suitably mounted on or adjacent to the machine. The sprocket 19 is driven continuously by a chain 20 which passes around a sprocket wheel 21 fixed on a shaft 22 to which the sprocket 19 is fixed.

The bottles, resting upright on the platforms of this conveyor chain are guided, as they are advanced thereby, by pairs of rails 25 the inner ends 25^a of which are curved inwardly to introduce the bottles, in upright position, to a turntable 29 the upper surface of which is on the same level with the upper bottle supporting surface of the bottle conveyor 16. Another pair of bottle guiding rails 30 are provided for guiding the bottles as they are discharged from the turntable and conveyed by the conveyor 16 to the delivery end of the machine. The tracks 30 have curved portions 30^a which extend outwardly from the turntable for the removal of the stamped bottles therefrom and the return of the bottles

to the conveyor 16. The travel of the bottle conveyor 16 from the left to the right of the machine as shown in Figs. 1 and 2 will advance the bottles entering the machine at the left to the turntable 29 and, after the bottles have been stamped and are discharged from the turntable, the bottle conveyor will continuously advance the stamped bottles to the discharge end of the machine where they may be received by a suitable table or other means for packing or other disposition.

The turntable 29 is supported on and secured to the upper side of a horizontal gear wheel 35 so that it rotates in unison with this gear wheel, and the gear wheel 35 is supported rotatably on the main frame and on a shaft 39 the upper end of which is fixed to a part 3 of the frame of the machine, as by a bracket 40. The gear 35 is driven by a gear 41 which is fixed on the upper end of a shaft 42 journalled in suitable bearings in the main frame, and the lower end of this shaft is connected by bevel gears 43 to a horizontal shaft 44 which is journalled in suitable bearings in the main frame. The shaft 44 is driven by suitable reduction gears 45 from a horizontal shaft 46, and the latter is driven continuously during the operation of the machine by any suitable means such as an electric motor 47 which may be connected by a belt 48 to a belt pulley 49 on the shaft 46. The shaft 44 also has a sprocket wheel 50 fixed thereon and around which the chain 20 for driving the bottle conveying chain 17 passes. Accordingly, the turntable and the bottle conveying chain will be driven continuously, and preferably the ratio of gearing is such as to cause the turntable and bottle conveyor to advance the bottles at the same speed.

The bottles are introduced from the bottle conveyor 16 onto the turntable 37 by a turnstile 55 so that they will be arranged in an annular series thereon and in properly spaced circumferential relation to be operated upon by an annular series of stamp affixing devices 38 which may be like those disclosed in my aforesaid prior application and mounted above and rotated in unison with the turntable, and the stamped bottles are removed from the turntable and returned to the bottle conveyor 16 by a turnstile 64. The turnstile 55 is fixed to a shaft 56 mounted adjacent to the edge of the turntable and driven by a gear 58 meshing with an idler gear 59, the latter meshing with another gear 61 which is of the same diameter, and is fixed to a shaft 62 on which the turnstile 64 is fixed, the gear 61 meshing with and being driven by the turntable gear 35 so that rotation of the turntable will rotate the turnstiles 55 and 64 in proper timed relation with the turntable to place the bottles thereon and remove them therefrom.

The stamp affixing devices are mounted in an annular series above the turntable 29, these devices rotating in unison with the turntable and applying and affixing stamps to the tops of the bottles. The construction and mode of operation of these stamp affixing devices is disclosed more fully in my aforesaid prior application, detail illustration thereof being deemed unnecessary for the purposes of the present invention.

The means provided by the present invention for feeding sheets, such as the stamps A, in the form of strips as shown in Fig. 24, comprises a magazine in which the sheets or stamps are placed in stacked relation. This magazine, as shown, comprises a rear wall 120, front wall

sections 121 and 122 which form a vertical slot between them, edge walls 123 and 124, and bottom wall 125, these walls forming a receptacle of a shape to receive and hold a stack of the stamps. The upper ends of the front walls 121 and 122 may be cut away as shown in Fig. 7 to facilitate the insertion of stacks of stamps into the magazine, and the stamps may be retained from displacement in the magazine by a spring finger 126 the lower end of which is fixed to the bottom wall 125 and the upper portion of which extends vertically between the front plates 121 and 122 and is engageable yieldingly against the edges of the stack of stamps in the magazine, the stamps resting on the bottom wall 125. The bottom wall 125 terminates short of the wall 124, thus providing an opening through which the lowermost stamps in the stack may be removed successively from the magazine, and a suction plate 127 is mounted in this opening, this suction plate having a suction aperture 128 which is open at the upper side of the plate so that it will underlie a stamp resting on the suction plate, the suction plate having a passageway 129 therein leading from the suction opening 128 to a nipple 130 to which a flexible suction hose 131 may be attached. The suction plate, as shown in detail in Fig. 8, is mounted on a shaft 132 which is journalled in a bearing 133 formed in or attached to the lower portion of the magazine plate 120, and this shaft has an arm 134 clamped or otherwise fixed thereon; this arm carrying a roller 135 which controls the operation of the suction plate relatively to the magazine. The magazine is pivoted at its upper corner above the suction plate to a relatively fixed bracket 136 which may be bolted or otherwise secured to a supporting plate 137, by a shaft 138 which is fixed by a flanged coupling 139 to said upper corner of the magazine. The shaft 138 is journalled to rotate in bearings 140 in the bracket 136 and it has an arm 141 fixed thereon and pivotally connected by a pin 142 to the upper end of a cam yoke 143. The lower end of this cam yoke straddles and is guided by a block 144 mounted loosely on a shaft 145, and the cam yoke carries a roller 146 which operates in the cam track 147 of a cam 148, the latter being suitably fixed to the shaft 145 to rotate therewith and operating to swing or oscillate the magazine to and fro about the shaft 138 as an axis. The shaft 145 is mounted in bearings in brackets 150 and 151 which are bolted or otherwise secured to the underside of the plate 137, and the bracket 150 has a cam 152 fixed to a side thereof, the roller 135 on the arm 134 attached to the suction plate operating in this cam and thereby controlling the operation of the suction plate. The cam 152 may be of rectilinear form and inclined as shown in Figs. 4 and 9 at such an angle that the upper face of the suction plate 127 will be maintained in a horizontal position, or substantially so, during the to and fro oscillation of the magazine by the shaft 138, as shown diagrammatically in Figs. 10, 11 and 12. The shaft 145 is driven continuously through bevel gears 155 from a shaft 156 the upper end of which is journalled in a bearing in the bracket 151, and the shaft 156 is driven continuously by a pinion 157 which is fixed thereon and meshes with the gear 41 which drives the turntable, as shown in Figs. 1 and 3. The plate 137 which carries the stamp feeding mechanism, including its operating shaft 145 and the driving shaft 156, is supported by rods 158 and braces 159 on the frame member 3.

The shaft 44 (Fig. 3) is connected by a chain 250 to a vacuum pump 251 which is of the reciprocating type having a piston 252, an air exhaust and air discharge valve 253 and an inlet check valve 254, the latter being connected to the flexible hose 131 attached to the suction plate 127, the pump being driven so that it makes one revolution to each cycle of the machine, each suction stroke of the pump being timed to take place immediately prior to the swing of the magazine toward the gripper wheel, whereby a suction will be produced at the aperture 128 which will hold the adjacent end of the lowermost stamp in contact with the suction plate as the magazine swings, thereby separating the lowermost stamp from the rest of the stamps in the stack. A spring finger 126^a attached at its upper end to the front of the magazine and having its lower end inturned supports the stack of stamps above the one separated therefrom.

A revoluble gripper cooperates with the suction plate of the magazine to remove the stamps successively therefrom. This gripper comprises a substantially circular wheel or disk 165 which is suitably fixed to the shaft 145 and is located adjacent to the suction plate. The wheel or disk 165 is grooved circumferentially, as shown at 166, and the major portion of its periphery is circular and provides a pair of stamp supporting edges 167 on its periphery which are preferably recessed at their outer sides to operate in a channel formed between a pair of stamp guides 168 supported by a yoke 168^a, a portion of these guides extending from the top of the gripper to the bottom thereof, concentrically of the gripper, and a continuation of these guides forming horizontal tangential extensions 169 supported in properly spaced relation by a bracket 169^a, as shown in Fig. 14. These stamp guides have grooves 170 in their inner faces which, in the curved portions of these guides, are concentric with the periphery of the gripper wheel 165 and are directly opposite to the stamp supporting surfaces 167 thereon, as shown in Fig. 19, and these grooves 170 extend longitudinally along the inner sides of the guide extensions 169. The grooves 170 form channels in which the edges of the stamps are guided to travel as they are withdrawn from the magazine, it being understood that the grooves are spaced apart a distance slightly greater than the width of the stamps. A portion of the periphery of the gripper wheel 165 is notched at 171 and this notch has a jaw 172 fixed therein to extend transversely of the gripper wheel. A gripping finger 173 is mounted to swing in the groove 166 at the notched side of the gripper wheel, this finger being fixed to a shaft 174 which is mounted rotatably in the gripper wheel and is provided with an operating arm 175 which is fixed thereto and carries a controlling roller 176. The end of the finger 173 has a jaw 177 thereon which is adapted to engage the relatively fixed jaw 172 in the gripper wheel, and a tension spring 178 attached at one end to the finger 173 and at its other end to a relatively fixed pin 179 in the gripper wheel tends to swing the jaw 177 into engagement with the jaw 172 and thereby grip the end of a stamp between them.

The operation of the gripper finger 173 is controlled by a cam 180 which is fixed by a set screw or other suitable means in the bearing 181 in the bracket 150, the shaft 145 being rotatable centrally of this cam, and the roller 176 controlling the gripper finger riding around the

periphery of this cam and being held in contact therewith by the spring 178 as the gripper revolves. The cam 180 is of such a shape and it is so set relatively to the gripper finger as to cause the gripper finger to drop onto the jaw 172 when the gripper finger reaches the top of the gripper wheel, as shown in Fig. 14, and to remain in contact with the jaw 172 until the gripper finger passes the lower side of the gripper wheel at which time the gripper finger will be retracted from the jaw 172, as shown in Fig. 16. The stamp magazine is so located relatively to the gripper wheel and the cam 148 is shaped to so oscillate the magazine as to cause the suction plate 127 to separate an end of the lowermost stamp in the magazine from the stack and to introduce the end of the stamp into a position to be gripped between the jaw 172 and the gripper finger 173 while the gripper revolves continuously, the rotation of the gripper wheel acting to withdraw the gripped stamp endwise from the magazine, after which the magazine retracts from the gripper wheel. This operation takes place at each revolution of the gripper wheel. As shown in Fig. 10 the stamp magazine is in its normal retracted position and the gripper wheel 165 has reached the position shown in this figure in its rotation. As the gripper wheel continues to revolve, the cam 148 swings the magazine on the shaft 138 as a center so that the suction plate 127 approaches the top of the gripper wheel, as shown in Fig. 11. During this swing of the magazine, the bottom thereof is tilted upwardly but the suction plate 127 is maintained in a horizontal position by the action of the cam 152 on the cam roller 135, in consequence of which the end of the lowermost stamp adjacent to the gripper wheel is separated from the remainder of the stamps in the magazine, the end of the stamp projecting slightly beyond the free end of the suction plate, and the suction plate, which is sufficiently narrow, enters the circumferential groove 166 in the gripper wheel behind the jaw 172. A moment later, as the jaw 172 reaches its uppermost position as shown in Fig. 12, the suction plate 127, due to the speed at which the magazine is oscillated, will have substantially overtaken the jaw 172 and brought the end of the stamp into a position to overlie it, at which moment the gripper finger 173 is allowed to drop by the cam 180 onto the end of the stamp and to thereby grip it between the jaw 177 on the gripper finger and the jaw 172 under the action of the spring 178, as shown in Fig. 14. The stamp gripped by the jaws 172 and 173 is carried, by the rotation of the gripper wheel 165, from the upper side thereof around the curved guides 168 and to the lower side of the gripper wheel, the stamp being guided by the circular rims 167 on the gripper wheel on which the stamp rests and by the grooves 170 in the guides in which the edges of the stamp travel. The stamp is thus drawn by the gripper wheel from the magazine by its leading end, and when this end of the stamp reaches the lower side of the gripper wheel it is engaged by means which transfers the stamp from the gripper wheel to the devices previously described which apply and affix the stamps to the bottles.

The stamp or other sheet transferring means provided by the present invention comprises an endless chain 185 which may be an ordinary roller chain, this chain passing around the sprocket 82 on which the stamp applying and affixing devices are mounted and around an idler sprocket

186 which is rotatable on a vertical shaft supported by a bracket 187 which fits in gib 188 on the underside of the plate 137, an adjusting screw 189 being mounted on the plate 137 and arranged to operate upon the bearing bracket 187 to adjust the sprocket 186 to take up slack or adjust the tension of the chain. The chain 185 carries at intervals along its length a series of stamp carriers 190 all of which may be of the same construction, each carrier having a saddle portion 191 by means of which it is bolted or otherwise fixed to links in the chain 185, and each carrier is in the form of a yoke having guiding fingers 192 projecting from one side thereof, and having a pair of shafts 193 rotatably mounted in the yoke near its ends, these shafts carrying hook like pins or needles 194. Each shaft 193 is provided with a spring 195 which acts thereon to swing its respective pin upwardly, and each shaft is provided with a block 196 which is fixed thereon and has an arm arranged to engage the respective yoke arm 192 and thereby arrest the swing of the pins when they assume substantially vertical positions. One of the shafts 193 has a cam 197 fixed thereon which is turned upwardly, and the other shaft 193 has a cam 198 fixed thereon and which is turned downwardly.

The chain 185 and the stamp carriers thereon are guided as they travel between the idler sprocket 186 and the sprocket 82 by rails 199 which are supported by brackets 200 fixed to a plate 201, the latter being supported rigidly from the plate 137 by a suitable number of rods 202. The chain during its travel passes between the rails 199 while the yokes 190 are suspended beneath these rails, and the arms 192 of the yokes ride on rails 203 which are mounted on the plate 201, as shown in Fig. 5.

Normally and as the stamp carrying yokes approach the gripper wheel 165, the pins 194 will be upturned and held in such position by the springs 195. As the leading pin on a yoke passes beneath the gripper wheel 165, the pin 194 on its leading end will project above the plane of the leading end of the stamp as it is brought to the lower side of the gripper wheel 165 and, while the leading end of the stamp is still gripped by the jaws 172 and 177, this pin will pierce the leading end of the stamp, immediately following which the gripper finger 173 is opened to release the leading end of the stamp, as shown in Fig. 16. The chain 185 and the stamp carrying yokes thereon are driven from the sprocket 82 so that they will advance at the same peripheral speed as that of the gripper wheel 165, and after the leading end of the stamp has been released by the gripper wheel the stamp is drawn through the curved guides 168 and then through the straight guide extensions 169 by the pins 194 on which it is impaled, the stamp being guided by its edges which engage in the grooves in the guide extensions 169, and when the rear or trailing end of the stamp approaches a point directly beneath the gripper wheel, the trailing pin 194 is retracted or lowered by engagement of its depending cam 198 which comes into contact with a cam 205 which is located in its path, thereby causing this trailing pin to be lowered and as it reaches a point directly beneath the center of the gripper wheel 165, the cam 196 reaches the end of the cam 205 and the spring 195 is thereby caused to snap this pin upwardly so as to pierce the trailing end of the stamp, as shown in Fig. 14. Fig. 4 shows the cam 198 as it is riding on the cam 205. In order to prevent damage to the stamp carrying mecha-

nism in the event the machine is turned backwardly for inspection, adjustment or other purposes, the cam 205 is carried by a plate 206 which is pivotally connected to the upper ends of a pair of parallel links 207, the lower ends of these links being pivotally mounted on plates 208 attached to the underside of the plate 201. The plate 206 is normally held in its raised operative position against a stop pin 209 by a tension spring 210, this spring however being yieldable to permit downward deflection of the cam 205 should the stamp carrier chain be moved backwardly.

The stamp, impaled upon and thus suspended between the upturned pins 194 of the stamp carrier, is conveyed by the chain 185 to the periphery of the sprocket 82, and as each stamp carrying yoke commences its travel around the periphery of the sprocket 82 it introduces the stamp between the top of a bottle as the same is fed onto the turntable 29 by the turnstile 55 and one of the stamp applying and affixing devices of the annular series which rotate with the turntable, it being understood that at this time the respective stamp applying and affixing device is in its fully elevated position. The moment the stamp applying and affixing device has descended and pressed the middle of the stamp upon the top or mouth of the bottle, the pins 194 are retracted to release the ends of the stamp. This releasing means is shown in detail in Figs. 20 and 21. It comprises a plate 210 bolted or otherwise fixed to the outer chain guiding rail 199 and having a pin 211 located in the path of the cam 197 on the shaft of the leading pin 194 so that as this cam engages the pin 211, the leading pin 194 is swung downwardly, thereby retracting this pin from the leading end of the stamp. Another plate 212 is bolted or otherwise fixed to the outer chain guiding rail 199 and this plate carries a pin 213 which is arranged in the path of the downturned cam 198 on the shaft of the trailing pin 194 so that as the stamp carrier advances this cam will engage the pin 213 and will be deflected thereby in a direction to retract the trailing pin 194, thereby releasing it from the trailing end of the stamp. The pins 211 and 213 are preferably so located as to cause both pins to be simultaneously retracted to release both ends of the stamp. In order to avoid damage to the stamp carrying mechanism in the event the machine is turned backwardly for inspection, adjustment or other purposes, the pins 211 and 213 are carried by levers 214 and 215 respectively which are pivoted at 216 and 217 respectively on the plates 210 and 212, the pins 211 and 213 operating in slots 218 and 219 in the respective plates and tension springs 220 and 221 normally holding the pins against the forward ends of the slots as shown in Fig. 20, reverse movement of the chain 185 however causing the pins 211 and 213 to be deflected in the slots and thereby permit the cams 197 and 198 to pass the pins 211 and 213 without obstruction.

As each stamp is drawn around the gripper wheel 165 it is provided with a strip of glue or other adhesive on that side of the stamp which is to be applied to the bottle. The glue applying means, which is shown more particularly in Figs. 4 and 6, comprises a segmental glue transfer roll 225 which is fixed to a shaft 226 journaled in a bracket 227, the roll 225 being located to operate between the curved guides 168 and to bear on and apply a strip of glue or adhesive longitudinally to the portion of the stamp which is exposed between these guides. The glue transfer

roll 225 is driven from the shaft 145 by a gear 228 fixed on said shaft and meshing with a gear 229 fixed on the glue roll shaft 226. In order to enable the glue transfer roll to be adjusted relatively to the gripper wheel and the stamp thereon, the bracket 221 which carries the glue transfer roll is pivoted at 230 to a bracket 231 which is bolted or otherwise fixed to the underside of the plate 131, a portion of the pivoted bracket 221 projecting to one side of the pivot 230 and being acted upon by a compression spring 232 between it and the bracket 231, and an adjusting screw 233 is threaded through the plate 131 and bears on a portion of the bracket 221 at the opposite side of the pivot 230, adjustment of the screw 233 in one or the other direction moving the glue transfer roll 225 toward or from the periphery of the gripper wheel 165. The glue transfer roll receives glue or adhesive from a glue roll 235 which rotates in contact therewith. This glue roll is fixed on a shaft 236 which is journaled in a bracket 237, the latter being slidable on gib 238 secured to the underside of the plate 131 so that the glue roll 235 may be adjusted toward and from the glue transfer roll 225. The glue roll 235 is provided with suitable means for supplying it with glue or other adhesive, a glue pot 240 being shown in the present instance which is of cylindrical form and having lugs 241 at its ends which are slideable adjustably in slots 242 in the bracket 237, the glue pot having a slot 243 in a side into which the periphery of the glue roll 235 may extend and thereby pick up glue or adhesive from the pot, and the pot being adjustable toward and from the glue roll by a pair of screws 244 threaded in the bracket 237 and bearing on the lugs 241, compression springs 245 bearing on the opposite sides of the lugs 241 and holding them in engagement with the screws. The glue roll and glue pot as a whole are adjustable toward and from the glue transfer roll 225 by a screw 246 which is mounted rotatably in the bracket 237 and threaded into the gib 238 on the underside of the plate 131.

If desired, means may be employed for moistening the stamps before they are applied to the bottles in order to soften the stamps and thus render them more pliable and thereby facilitate their application to the bottles so that they will lie in intimate relation with the bottles. Such means may consist of a brush 260 (Fig. 4) mounted above the path of travel of the stamps as they are advanced by the chain 185 toward the bottles, this brush being located in a position to brush over the stamps as they are suspended between and advanced endwise by the pins 194, and supplied with water at a suitably slow rate through a hose 261 leading from a suitable reservoir 262.

In the operation of the machine, the bottle conveyor is driven continuously to convey the bottles from the left toward the right in Figs. 1 and 2 by the motor 47 which also operates to rotate the turntable 27 and the sprocket 82 continuously and to also drive the stamp feeding shaft 145 continuously as well as to operate the pump 251 continuously. The turnstile 55 feeds the bottles successively around the curved portions 25a of the guide rails onto the turntable while the latter revolves, thereby placing the bottles on the turntable in an annular row, and as the stamp applying and affixing devices 38 carried by the sprocket 82 are also rotated in unison with the turntable and are spaced circumferentially thereof at intervals corresponding to the intervals at which the bottles are placed on

the turntable by the turnstile 55, the bottles will be placed on the turntable in positions immediately beneath the respective stamp applying and affixing devices.

5 The stamp conveyor chain 185, which is driven from the sprocket 82 and hence at a speed corresponding with the speed of rotation of the row of bottles and the stamp applying and affixing devices, is supplied with gummed stamps A successively by the gripper wheel, the stamps being impaled upon the pins 194 so that they are suspended between these pins, and the stamp conveyor chain carries the stamps to the stamp applying and affixing devices in a path which is tangential to the circular path of rotation of said devices, the stamps being thus introduced successively between the top of each bottle on the turntable and the respective stamp applying and affixing device.

10 As the stamp applying and affixing devices rotate, the device beneath which the stamp has just been introduced operates to apply the stamp to the top of the bottle, immediately following which the pins 211 and 213 operate upon the stamp carrying pins 194, incident to the travel of the chain 185, and retract or withdraw them from the ends of the stamp, thereby releasing the ends of the stamp for application to the bottle.

15 The stamp feeding means, including guides to engage the edges of the stamps and thereby guide them while they are being conducted by the gripper wheel to the stamp transferring means, insures the placing of the stamps in properly aligned position on the carrying pins, and such alignment of the stamps is maintained until the stamps are placed on the bottles.

20 The means provided by the present invention for transferring the stamps from the stamp feeding means to the bottles or the like for application thereto not only enables the stamps to be readily brought into applying position between the bottles or other containers and their affixing devices, but by carrying the stamps endwise while suspended by their ends on carrying pins, applying of the stamps uniformly and evenly to the bottles or other containers is ensured. By withdrawing the pins from the ends of the stamp immediately after the stamp has been applied to the bottle or other container, the stamp is released from its carrier without tearing and thus mutilating the ends of the stamps.

25 Although the sheet feeding and transferring means has been herein described as applied to a bottle stamping machine for applying and affixing stamps such as revenue stamps to the tops of bottles, it will be evident that sheet feeding and transferring means constructed in accordance with the present invention may be employed for feeding and supplying labels or similar sheets to various other articles for various purposes, and it is to be understood that, in the broader aspects of the invention, references in this specification to stamps are intended to include such labels or similar strip-like or sheet-like objects, and that the invention is not limited in its use to the stamping or labelling of bottles but is applicable to various containers in which such strip-like or sheet-like objects are to be fed and supplied.

30 I claim:

35 1. Sheet feeding means comprising a magazine to contain a stack of sheets, a rotatable gripper wheel, means for separating a sheet from the stack in the magazine, means for relatively moving the magazine and gripper wheel to bring an end of the separated sheet into a position to

be gripped by the gripper wheel, and means for rotating the gripper wheel unidirectionally to engage said sheet and remove it from the magazine.

2. Sheet feeding means comprising a magazine to contain a stack of sheets, means for separating a sheet from the stack in the magazine, a rotatable gripper wheel carrying a gripper, means for moving the magazine to bring an end of the separated sheet into position to be gripped by the gripper on said wheel, and means for rotating said gripper unidirectionally to grip the sheet and remove it from the magazine.

3. Sheet feeding means comprising a magazine to contain a stack of sheets, means for separating an end of a sheet from the stack, a rotatable gripper wheel carrying a gripper to grip said end of the sheet and withdraw it from the magazine, and a guide extending around a portion of the gripper wheel and having means for engaging the edges of the sheet and thereby guiding it.

4. Sheet feeding means comprising a magazine to contain a stack of sheets, a separator carried by but movable relatively to the magazine for separating the lowermost sheet from the stack, a rotatable gripper wheel carrying a gripper, means for moving the magazine and separator toward the gripper wheel, means for operating said separator during the movement of the magazine to separate a sheet and bring an end thereof into position to be engaged by said gripper, and means for operating said gripper to engage an end of the separated sheet and withdraw it from the magazine.

5. Sheet feeding means comprising a pivotally mounted magazine to contain a stack of sheets, a rotatable member carrying a gripper, means mounted to swing with the magazine about its pivot for separating an end of a sheet in the magazine from the rest of the stack therein, means for swinging the magazine and said separating means toward said member during its rotation to bring the separated end of the sheet into position for engagement by the gripper, and means for operating the gripper to grip the end of the sheet at the moment of engagement of the gripper therewith.

6. Sheet feeding means comprising a magazine to contain a stack of sheets and having a suction member pivoted at one end of its bottom to engage an end of the lowermost sheet, means for lowering said suction member periodically, and a reciprocating pump connected to said suction member and operative on its suction strokes during the lowering movements of said suction member to separate the lowermost sheet from the remainder of the stack.

7. Sheet feeding means comprising a pivoted magazine to contain a stack of sheets, a member pivoted on the magazine and operative to separate a sheet from the stack in the magazine, a gripper to engage an end of the sheet separated by said member and withdraw it from the magazine, and means operative by pivotal movement of the magazine for operating said sheet separating member.

8. Sheet feeding means comprising a gripper, a magazine to contain a stack of sheets and pivoted to swing at its lower end toward and from the gripper, a member carried by the lower portion of the magazine for separating the lowermost sheet from the stack therein for engagement by the gripper, and means for operating said member and guiding it toward the gripper during the swing of the magazine.

9. Sheet feeding means comprising a gripper, a magazine to contain a stack of sheets and pivoted on a substantially horizontal axis to swing at its lower end toward and from the gripper, a sheet separator pivoted on the lower portion of the magazine, and means for maintaining the separator in a substantially horizontal position during the swinging movements of the magazine.

10. Sheet feeding means comprising a gripper, a magazine to contain a stack of sheets and pivoted on a substantially horizontal axis to swing at its lower end toward and from the gripper, a sheet separator pivoted on the lower portion of the magazine, and means including a relatively stationary cam for maintaining the separator in a substantially horizontal position during the swinging movements of the magazine.

11. Sheet feeding means comprising a rotatable gripper wheel having a peripheral groove and carrying a gripper, a magazine to contain a stack of sheets and mounted to swing its lower portion toward and from the gripper wheel, a sheet separator mounted on the lower portion of the magazine for lowering and raising movements and having a relatively narrow portion to enter the peripheral groove in the gripper wheel, and means for lowering the separator during each swing of the magazine toward the gripper wheel to separate a sheet from the stack and position its end for engagement by the gripper.

12. Sheet feeding means comprising a rotatable gripper wheel carrying a gripper, means for feeding an end of a sheet to the gripper, and guides extending around a portion of the periphery of the gripper wheel and having grooves therein to receive opposite edges of the sheet and through which the sheet is drawn by the gripper.

13. Sheet feeding means comprising a rotatable gripper wheel carrying a gripper, means for feeding an end of a sheet to the gripper, and guides extending around a portion of the periphery of the gripper wheel and having grooves therein to receive opposite edges of the sheet for directing it past adhesive applying means and through which the sheet is drawn by the gripper.

14. Sheet feeding means comprising a rotatable gripper wheel, spaced guides extending around a portion of the periphery of said wheel, a gripper on said wheel operative to grip an end of a sheet and draw it around said wheel between said guides, and transferring means movable past the gripper wheel and carrying devices operative to receive the leading and trailing ends of the sheet as they are drawn between said guides.

15. Sheet feeding means comprising a rotatable gripper wheel, spaced guides extending around a portion of the periphery of said wheel, a gripper on said wheel operative to grip an end of a sheet and draw it around said wheel between said guides, and transferring means movable past the gripper wheel and carrying pins operative to pierce the leading and trailing end portions of the sheet as they are drawn between said guides.

16. Sheet feeding means comprising a rotatable gripper wheel, spaced guides a portion of each of which is curved and extends around a part of the periphery of said wheel and another portion of which extends substantially tangentially from said periphery, a gripper on said wheel operative to grip an end of a sheet and draw it around the curved portion of the guides, transferring means movable past the gripper wheel and longitudinally of the tangentially ex-

tending portion of the guides and carrying pins one of which is arranged to pierce the leading end of the sheet as it is drawn by said gripper and the other of which pins is arranged to pierce the trailing end of the sheet, and means for operating the gripper to release the sheet after the first-mentioned pin has pierced the leading end of the sheet, the pin which pierces the leading end of the sheet being operative to complete the drawing of the sheet between said curved portion of the guides and to draw it through the tangentially extending portion of the guides.

17. Sheet feeding means comprising a rotatable gripper wheel, spaced guides a portion of each of which is curved and extends around a part of the periphery of said wheel and another portion of which extends substantially tangentially from said periphery, a gripper on said wheel operative to grip an end of a sheet and draw it around the curved portion of the guides, transferring means movable past the gripper wheel and longitudinally of the tangentially extending portion of the guides and carrying pins one of which is arranged to pierce the leading end of the sheet as it is drawn by said gripper

and the other of which pins is provided with means for snapping it into piercing engagement with the trailing end of the sheet, said pins suspending the sheet between them and operating to advance the sheet endwise between the tangentially extending portion of the guides.

18. Sheet feeding means comprising a rotatable gripper wheel, spaced guides a portion of each of which is curved and extends around a part of the periphery of said wheel and another portion of which extends substantially tangentially from said periphery, a gripper on said wheel operative to grip an end of a sheet and draw it around the curved portion of the guides, transferring means movable past the gripper wheel and longitudinally of the tangentially extending portion of the guides and carrying pins one of which is arranged to pierce the leading end of the sheet as it is drawn by said gripper and the other of which pins is provided with a cam for snapping it into piercing engagement with the trailing end of the sheet, said cam being yieldable into an inactive position when said transferring means is moved backwardly.

25

RICHARD C. TALBOT.
